DESIGN FOR DECORATIVE PAPER

Robert F. Hobbs, Jr., Washington, N. J., assignor to Hazen Paper Company, Holyoke, Mass.

Application December 16, 1936, Serial No. 66,579

Term of patent 7 years

To all whom it may concern:

Be it known that I, Robert F. Hobbs, Jr., a citizen of the United States, residing in Washington, county of Warren, State of New Jersey, have invented a new, original, and ornamental Design for Decorative Paper, of which the following is a specification, reference being had to the accompanying drawing, forming part thereof.

The figure of the drawing is a plan view of a piece of decorative paper showing the design.

I claim:

The ornamental design for decorative paper, as shown.
